RECEPTACLE FILLING MACHINE

Irwin I. Kotcher, Brooklyn, N. Y.

Application May 19, 1937, Serial No. 143,583

7 Claims. (Cl. 226—95)

This invention is a machine for filling portable receptacles, and is particularly designed for filling receptacles of the type forming the subject matter of a patent granted to me February 8, 1938 No. 2,107,614, the receptacles being mainly designed for the vending of milk and the like.

The present invention together with its objects and advantages will be best understood from a study of the following description taken in connection with the accompanying drawings wherein:

Figure 1 is a side elevational view of the machine.

Figure 2 is an end elevational view thereof. Figure 3 is a detail view through a portion of the filling mechanism and showing a cam arrangement for raising and lowering the measure container forming part of such mechanism.

Figure 4 is a vertical sectional view through the filling mechanism or part of the machine and showing a container or receptacle lifting device hereinafter more fully referred to.

Figure 5 is a view somewhat similar to Figure 4 but taken through the receptacle closing part of the device.

Figure 6 is a detail sectional view showing in top plan an arrangement of elements forming part of the receptacle filling mechanism of the machine.

Figure 7 is a view similar to Figure 6 but taken through the receptacle closing part of the device.

Figure 8 is an enlarged vertical sectional view illustrating certain details of the receptacle filling part of the device.

Figure 9 is a fragmentary detail view partly in section and partly in elevation showing a gripping finger arrangement at one end of the receptacle filling part of the device.

Figure 10 is a view similar to Figure 9 and showing a finger arrangement at a relatively opposite end of the receptacle filling part of the device.

Figure 11 is a fragmentary plan view showing the shield at the lower end of a barrel forming part of the receptacle filling assembly of the device.

Figure 12 is a vertical sectional view through the receptacle closing mechanism of the device.

Figure 13 is a bottom plan view showing certain details of the receptacle closing device.

Figure 14 is a fragmentary detail sectional view showing a finger assembly at one end of the receptacle closing part of the device and—

Figure 15 is a top plan of the assembly shown in Figure 14.

Figure 16 is an enlarged detail sectional view through the receptacle closing part of the device and illustrating certain details hereinafter more fully referred to.

Figures 17, 18 and 19, are elevational views of cams hereinafter more fully referred to.

Referring in detail to the drawings it will be seen that the device comprises a suitable frame 5 in which are mounted grooved roller assemblies, including upper and lower roller assemblies 6 and 7 at each end of the frame and upper and lower roller assemblies 8 and 9 intermediate the ends of the frame. Trained over the rollers 8 and 9 are endless conveyor elements 10 in the form of endless coil springs.

Mounted at one end of the frame 5 is a receptacle filling apparatus indicated generally by the reference numeral 11.

In this form of the invention the apparatus 11 comprises a tank 12 adapted to receive milk or the like, from a source of supply through a pipe 13. Depending from the tank 12 at the ends of the tank are guide rods 14 which work through bearing sleeves 15 provided in the upper ends of channel members 16 mounted on and rising from opposite sides of the frame 5.

For raising and lowering the tank 12 and to secure the same at the desired elevation relative to the conveyor there is provided an adjusting screw 17 that has one end swivelly mounted on a cross bar 18 connecting an end pair of channel members 16 and its upper end threaded through the base flange 19 of the tank 12. A suitable handle 20 is provided for the lower end of the screw and obviously by turning the screw the tank 12 is secured at the desired position of vertical adjustment.

Extending downwardly from the bottom of the tank 12 are a plurality, in the present instance eight discharge tubes 21, and extending through each discharge tube 21 is a valve stem 22 provided on its lower end with a valve member 23 normally seating against a seat 24 that has a tubular stem 25 sleeved on the discharge tube 21. A suitable coil spring 26 normally urges the seat 24 downwardly into engagement with the valve member 23.

Suspended from the bottom of the tank through the medium of suspension rods 27 is a measuring tank 28 dividing into a plurality of compartments 29, the number of compartments corresponding to the number of discharge tubes 21 and each compartment of predetermined capacity.

Extending laterally from each compartment 29 is a sight tube 30 suitably supported through the medium of a frame structure 31 and through

the medium of which the contents of a compartment 28 may be viewed.

Each compartment 28 has extending downwardly therefrom a discharge tube 32 that is closed at its lower end and at said lower end is provided with lateral discharge ports 33 arranged in relatively spaced circumferential relation about the periphery of the discharge tube.

For controlling the ports 33 there is slidably 10 on the tube 32 a sleeve valve 34 normally urged downwardly to a closing position through the medium of a coil spring 35. At its lower end the sleeve valve 34 is provided with a plate-like head 36 opposite side edges of which are down turned 15 as shown, the head 36 being of a size to accommodate the upper end of a receptacle 37.

For simultaneously raising a plurality of receptacles 37 into contact with the valve heads 36 for causing the sleeve valve 34 to move upwardly 20 on the lower ends of the tubes 32 to extend inwardly of the receptacles 37 through the filling and pouring openings 38 in the top of said receptacles there is provided a raising and lowering structure indicated generally by the reference numeral 39.

The raising and lowering structure 39 in the present instance consists of a block 40 having extending upwardly therefrom a series of ribs 41 that are adapted to pass upwardly between conveyor elements 10 to engage the bottom of the receptacle 37 and lift the receptacle from the continuously moving conveyor elements 10.

Block 40 operates between a pair of suitably mounted guides 42 and for raising and lowering 35 the block 40 there are provided a pair of standards 43 to the upper ends of which are pivoted as at 44 arms 45 which at one end are equipped with rollers 46 that have bearing engagement with the underside of the block 40 as shown in 40 Figure 1.

Mounted in the bottom of the frame 5 is a suitable structure 47 in which is mounted a vertical slide 48 carrying a roller 49 and a spring 50 normally urges the slide 48 upwardly.

Extending from opposite sides of the slide 48 and working through suitable slots provided therefor in the guide 47 are ears 51 which are operatively connected with the arms 45 through the medium of links 52.

Suitably journaled in the frame 5 is a shaft 53 on which is mounted a cam 54 which cooperates with the roller 49 for moving the slide 48 downwardly against the action of spring 50 whereupon a downward pull is exerted on the arms 45 for swinging the latter vertically upwardly to raise the jack plate 40 to elevate the receptacles 37 as and for the purpose above mentioned.

For raising and lowering the measuring tank 28 in proper synchronism to the raising and lowering of the receptacle 37 there are provided on the shaft 53 cams 55 on the peripheries of which ride rollers 56 journaled in the lower ends of rods 57.

Rods 57 are arranged in pairs and the rods of each pair at their lower ends are connected by a cross bar 58 which is suitably provided to accommodate the aforementioned roller 56.

As clearly shown in Figure 3 rods 57 work through suitable guides 59 provided therefor on the frame 5 and at their upper ends are provided with sockets 60 which receive the lower ends of arms 61 secured at the desired position of adjustment through the medium of set screws 62.

At their upper ends arms 61 are connected by a cross bar 63 which is secured as at 64 to an adjacent end of the measuring tank 28.

It will thus be seen that if tank 28 is caused to move upwardly, the flanges 65 about the 5 openings provided in the top walls of the compartments 28 engage the valve seats 24 urging the latter upwardly against the action of springs 26 and out of engagement with the valve members 23 so that milk or the like from the tank 10 will flow into the compartments 28 for filling the compartments 28 subsequent to each operation of filling the receptacles 37.

In this connection it may be mentioned, and as shown in Figure 8, that for controlling the supply of milk or the like from the source of supply to the tank 12 and to insure the maintenance of a proper liquid level within the tank 12, there is provided in the tank 12 a float 66 that will be suitably connected with valve means 15 forming part of the means for feeding the milk 20 or the like to the tank 12.

Mounted above one end of the frame 5 is a battery of capping devices indicated generally by the reference numeral 67. The capping devices 25 67 are, as will be clear from a study of Figure 16 conventional being of a well known structure and respectively embodying generally a spring pressed vertically shiftable casting 68 which includes a magazine 69 for the caps 70 and which 30 casting is also provided to accommodate a follower 71 for successively positioning the caps 70 in line with a plunger 72.

For raising the filled containers 37 into contact with the flanged part 73 of the cappers for applying the cap 70 to the containers there is provided a receptacle raising and lowering device indicated generally by the reference numeral 14. Referring more specifically to Figures 5 and 14, it will be seen that the carton raising and lowering device 14 embodies a plate 75 working between a pair of guides 76. Arranged on the plate 75 are a plurality of jack members 77, each of which as clearly shown in the figures comprises a substantially U-shaped member having intermediate webs or upstanding ribs 78 that work through the spaces between the conveyor elements 10. There is one jack 77 for each container.

The plate 75 is constrained to move vertically 50 through the medium of pins 79 projecting from opposite edges thereof and working in vertical slots 80 provided in the guides 76.

For causing the jack members 77 to separate or move in a position away from one another for spreading the receptacles 37 apart as they move up into engagement with the flanged parts 73 of the cappers there are provided on opposite sides of the jacks 77 pins 81 that work in suitable bayonet slots 82 arranged at the proper angles 60 and provided in the guides 76 as shown in Figure 5. It will thus be seen that through the medium of pins 81 and slots 82 jack members 77 as they move upwardly also move in a direction substantially longitudinal of the guides 76 until they 65 reach a predetermined point in their upward movement whereupon they then move vertically upwardly perpendicularly into engagement with the cappers. The movement of the jack elements 77 and the cartons thereon is clearly detailed by 70 broken lines in Figure 5.

It will thus be seen that upon a filling of a predetermined number of containers 37 the filled containers are lowered on to the conveyor elements 10 and are carried thereby into a position 75

to be engaged by the jacks 77 which then go into operation to move the receptacles 37 into engagement with the cappers whereupon the caps or closures are applied to the containers, after which the containers are lowered on to the conveyor elements 10 to be carried towards the discharge end of the device to be removed from the device.

For raising and lowering the jacks of the device 14 the same includes a guide 83 in which 10 works a slide 84 having ears 85 operating through slots in opposite sides of the guide 83 and connected by links 86 with arms 87 pivotally mounted on standards 88. Arms 87 have roller equipped ends 89 bearing on the plate 75. Mounted on 15 shaft 53 is a cam 90 that cooperates with a roller 91 suitably journaled in the slide 84 for effecting a downwardly movement of the slide 84 in opposition to spring 92 for swinging the arms 87 upwardly to raise the jacks of the device as and 20 for the purpose explained in detail.

Mounted at the forward end of the jack structure 39 and arranged to engage a carton for arresting the movement of following cartons upon the placing of the proper number of cartons over 25 the jack assembly 39, without affecting the movement of the conveyors 10 and pivoted at 93 are fingers 94 which through the medium of springs 95 are normally urged inwardly toward one another to engage opposite sides of a carton or 30 receptacle 37 as clearly shown in Figure 9. The jaws or fingers 94 have the shanks thereof equipped with cams 96 that cooperate with cams 97 carried by the jack elements 40 for normally holding the jaws or fingers 94 in the spread apart 35 position shown in Figure 9.

Obviously, as the jack 40 moves upwardly to engage the carton 37 positioned thereover, cams 96 and 97 coact to permit the jaws or fingers 94 to swing inwardly in response to springs 95 to 40 engage a carton 37 to arrest the movement of that carton and those following said cartons during the filling operation of those cartons being raised upwardly by the jack element 40.

To arrest the movement of the cartons as they 45 move into position over the jack element 40 there are provided at the end of the jack assembly 39 remote from the jaws or fingers 94 a pair of oppositely disposed jaws or fingers 98 pivoted as at 99 and normally urged by springs 100 away 50 from one another and out of the path of the containers or receptacles 37. At the upper ends the jaws or fingers 98 operate through suitable openings 101 provided therefor in guide rails 102 to normally extend through said openings in the 55 path of the cartons.

At their lower ends the jaws or fingers 98 are 60 equipped with rollers 103 with which cooperate cams 104 provided at the adjacent end of the jack element 40 and which serves to normally urge the upper ends of the jaws or fingers 98 inwardly into the path of the carton with the jack element 40 in lowered position.

From the foregoing it will be apparent that 65 normally with the jack element 40 in lowered position jaws or fingers 98 are in the position shown in Figure 10 to arrest the movement of the cartons 37 as they move into position above the jack element 40. As the jack element 40 moves upwardly cams 104 move out of engagement with the roller equipped ends 103 of the fingers 98 70 permitting these fingers under action of springs 100 to spread apart. At the same time, and as the jack member 40 moves upwardly cams 97 move upwardly therewith in a manner to cooperate 75 with the cams 96 of fingers 94 permitting the

latter to move inwardly to engage a carton 37 following immediately the last carton positioned above the jack element 40 so that this last carton and those following it are held against movement during the actual filling operation of a selected 5 number of cartons or containers 37.

After the cartons have been filled jack element 40 moves downwardly to reposition the filled cartons onto the conveyor 10 to be carried thereby into position over the jack element 77. As the 10 jack element 40 moves downwardly to reposition the filled cartons onto the conveyor 10 cams 97 move downwardly into engagement with cams 96 for spreading the jaws or fingers 94 apart so that the next group of cartons to be filled may move 15 into position over the jack element 40 as the filled cartons move into position over the jack element 77.

When the second group of cartons are properly positioned over the jack element 40 the latter will 20 have moved downwardly below the conveyor 10 sufficiently to cause the cams 104 to engage the ends 103 of arms 98 causing the upper ends of these arms to move inwardly toward one another and thus arrest further movement of this second 25 group of cartons thereby holding the same in a position to be raised upwardly into filling position upon the return or upward movement of the jack 40.

To stay movement of the leading filled cartons 30 or containers 37 and thereby permit the filled cartons or containers to properly group over the jack assembly 14 there is provided at one end of the jack assembly a pair of opposed stop fingers or arms 105 pivoted as at 106 and normally urged 35 by suitably provided springs 107 to swing in reverse direction relative to one another and out of the path of the cartons or containers 37. Adjacent their pivoted ends the fingers 105 normally engage against the underside of the vertically movable plate 75 as shown in Figure 14. It will thus be seen that after the filled cartons have been properly grouped over the jack elements 77 and these elements move upwardly 40 springs 107 act on the fingers 105 to spread the latter apart. After the capping operation has been completed jacks 77 with the cartons thereon move downwardly and when these jacks have moved downwardly a distance sufficient to permit the bottoms of the capped cartons to rest on the 50 conveyor element 10 downward movement of the jack element is arrested, as will be hereinafter made manifest, for an interval of time sufficient to maintain the fingers 105 sufficiently spread apart to permit the entire group of caps or sealed 55 containers 37 to pass between said fingers. When this has been accomplished downward movement of the jack elements 77 is resumed and as these jack elements reach the limit of their downward movement fingers 105 move into final position 60 overlying the conveyor elements 10 to serve as a stop means for the next group of filled containers.

As shown in Figures 17 to 19, inclusive cams 90, 55 and 54 are so shaped to insure a proper timing of the several operations. 65

Cams 55 which control the raising or lowering of the measuring tank 28 is shown in Figure 18 and embodies a cam hump 55a with which the roller 56 is engaged for effecting a raising of the measuring tank 28, it being apparent that as cam 70 hump 55a moves into peripheral contact with the roller 56 measuring container 28 moves upwardly to effect an upward movement of the valve seats 24 to supply the compartments 29 with milk from the tank 12, and as the cam hump 55a moves out 75

of contact with the roller 56 the measuring tank 28 slowly moves downwardly for effecting a seating of the valve seats 24 against the valve stems 23 to cut off the supply of liquid from the tank 12 to the compartments 29.

Cam 54 is provided with a cam hump 54a which is in contact with the roller 49 during an actual filling of the carton 37; and said cam 54 has a cam part 54b with which the roller 49 is in contact during the crowding of the empty containers 37 on the conveyor element 10 to align with the discharge valves of the measuring chambers 29. Roller 49 is in contact with the section 54c of cam 54 during the passing of the charged containers 37 from the filling end of the device to the capping or closing end of the device.

When the loading part 54b is in contact with roller 49, member 40 is in lowered position so that the cams 97 are in engagement with the cams 98 and the arms 94 are spread apart so that these arms will not contact the cartons. Also the cams 104 will be in engagement with the rollers 103 of arms 98 so that these arms 98 will be in holding position as shown in Figure 10. Then as the high part 54a of cam 54 engages the roller 49 the member 40 will be raised, thus causing the cams 97 to release the cams 98 to permit the arms 94 to engage a carton and the cams 104 will move out of engagement with the rollers 103 so that the springs 100 will spread the arms 98 apart. Then the part 54c of cam 54 will engage the roller 49 to cause the member 40 to move downwardly but not to its full extent. This downward movement is sufficient to cause the cams 97 to move the arms 94 apart but is not sufficient to cause the cams 104 to engage the rollers 103 so that the arms 98 remain spread apart and thus will not prevent the movement of the filled cartons from the filling station to the capping station. Then the part 54b of cam 54 comes into engagement with the roll 49 to permit a slight downward movement of the member 40 which causes the cams 104 to engage the rollers 103 so as to move the arms 98 toward each other into holding position. It will be understood that when part 54c of cam 54 is engaging the roller 49 the member 40 will have moved downwardly to a sufficient extent to place the cartons on the conveyor so that the cartons will move with the conveyor but said member 40 will still be in a position where the cams 104 will not engage the rollers 103 so that the arms 98 will remain spread apart until part 54b will have engaged the roller 49.

That part of cam 54 between the low portion 54b and the high portion 54a is so formed that its engagement with the roller 49 will cause the lifting means to raise the jack or member 40 so quickly that the jack will lift the cartons from the conveyor practically simultaneously with the upper bent ends of the arms 98 moving outwardly to releasing position. Thus there is no appreciable movement of the cartons by the conveyor, after the arms move outwardly before the cartons are lifted from the conveyor by the jack 40.

While the filled containers are passing from the filling end of the device to the capping or closing end of the device section 90a of cam 90 is in contact with roller 91. During the actual capping operation cam hump 90b of cam 90 is in contact with roller 91; while during the passing of the capped and closed containers between the spread apart fingers or jaws, 105, cam hump 90c of cam 90 is in contact with roller 91.

In this connection it will be further observed that engagement of cam 90c with roller 91 retards

the downward movement of the jack plate 75 sufficiently and for a time interval necessary to maintain fingers 105 spread apart a distance sufficiently to permit the capped and closed cartons or containers 37 to pass therebetween; fingers 105 moving into the full line position shown in Figure 14 as cam hump 90c moves off the roller 91 and the section 90a of the cam 90 moves into peripheral contact with the roller 91. While hump 90c is engaging roller 91 jack plate 75 will have moved downwardly a sufficient distance to place the cartons on the conveyor but not far enough to move the arms 105 into carton engaging position, this not occurring until the roller 91 engages the part 90a of cam 90.

As will be clear from a study of Figures 1, 12 and 16 the individual capping units 108 are mounted on a bar 109 that is constrained to move vertically between a pair of uprights 110. To secure the capping elements at the desired position of vertical adjustment there is provided an adjusting screw rotatably mounted at one end as at 112 and at said end provided with a crank handle 113. Screw 111 has a threaded portion threaded through a lug 114 carried by bar 109 and obviously by turning the screw 111 the bar 109 is caused to move vertically up or down as the case may be for effecting a proper adjustment of the capping element.

Since the individual capping elements are of more or less conventional structure a detailed description thereof is deemed unnecessary. It is, however, pointed out that the follower 11 of each capping element has a suitable link connection 115 with an arm 116 secured to plunger rod 72 as at 117 in a manner to insure a projecting and retracting of the plunger or follower element 11 incidental to a raising and lowering of the vertically shiftable parts of the capping element for feeding the caps 70 successively in position for application to the container.

Having thus described the invention, what is claimed as new is:

1. In a device of the character described, and in combination, an endless conveyor, an elevator block movable vertically relative to the conveyor, a pair of standards, arms pivoted to said standards and having ends in bearing engagement with the block for raising the latter, a vertically shiftable slide, supporting means for the slide, means operatively connecting said slide with said arms for swinging the latter on their pivots to raise and lower said block, a cam rotatably supported above said slide and having peripheral contact with the slide for controlling the vertical movement of the latter, and spring means acting on said slide in opposition to said cam.

2. In a device of the class described, a constantly moving conveyor for articles placed thereon, holding means for holding an article against movement on the conveyor, means for normally holding the holding means out of holding position, an elevator located under a part of the conveyor and when in lowered position holding the holding means in holding position and means for first raising the elevator to move an article off the conveyor and hold the article for a period of time in raised position and then lowering the elevator to place the article back upon the conveyor and then, after a period of time, to fully lower the elevator to move the holding means in holding position.

3. In a device of the class described, a constantly moving conveyor for articles, a vertically movable elevator, a pair of holding arms pivot-

ally supported and having upper portions for engaging an article on the conveyor for holding the article against movement by the conveyor, spring means for normally holding the arms separated 5 and out of engagement with an article, said elevator when in lowered position engaging parts of the arms for moving the arms into holding position and cam actuated means for first moving the elevator to lift an article off the conveyor 10 and hold it above the conveyor for a period of time and to then lower the elevator to place the article back upon the conveyor and then finally after a period of time lowering the elevator into its lowest position to engage the arms to move the 15 arms into holding position.

4. In a device of the class described, a supporting frame, a reservoir at the top of the frame, a member supported for vertical movement under the reservoir and containing a horizontal row of 20 chambers, a horizontal row of valve means depending from the reservoir, one for each chamber, said valves moving to open position when the chamber member is moved upwardly to permit liquid to pass from the reservoir into said 25 chambers, valve means depending from the chamber member, there being one valve means for each chamber, a constantly moving conveyor for containers, an elevator for moving a number of containers upwardly off the conveyor against the 30 valve means of the chamber, means for opening said means to permit liquid to flow from the chambers into the containers, holding means for holding the containers against movement on the conveyor and with the containers located under 35 the valve means of the chamber member, second holding means for holding containers on the conveyor in front of the containers being filled, a drive shaft rotatably supported in the frame, a cam carried by the shaft, means actuated by the 40 cam for moving the chamber forming member vertically, a second cam carried by the shaft and means actuated by the second cam for first raising the elevator to raise containers off the conveyor against the valve means of the chamber 45 member, then lowering the containers back upon the conveyor and finally, after a period of time, moving the elevator to fully lowered position to place the first-mentioned holding means in holding position and to move the second-mentioned holding means out of holding position.

5. In a receptacle filling machine, a supporting frame, a reservoir at the top of the frame, means for adjusting the reservoir vertically, normally closed valve means depending from the reservoir, 55 a vertically movable member having a plurality of chambers therein located under the reservoir and when moved upwardly against the valve means will open the valve means to permit liquid to flow from the reservoir into the chambers of 60 said member, a drive shaft, cams carried thereby, roller carrying members connected with the chamber member and having the rollers engaging the cams, means for adjusting the length of the roller carrying members, a conveyor for supporting 65 receptacles, an elevator, a cam on the shaft, means operated thereby for raising and lower the elevator, valve means carried by the chamber member and opened by the receptacles when the same are raised by the elevator to permit liquid

from the chambers to flow into the receptacles.

6. In a receptacle filling machine, a supporting frame, a reservoir at the top of the frame, means for adjusting the reservoir vertically, normally closed valve means depending from the reservoir, 5 a vertically movable member having a plurality of chambers therein located under the reservoir and when moved upwardly against the valve means will open the valve means to permit liquid to flow from the reservoir into the chambers of said member, a drive shaft, cams carried thereby, roller carrying members connected with the chamber member and having the rollers engaging the cams, means for adjusting the length of the roller carrying members, a conveyor for supporting 10 receptacles, an elevator, a cam on the shaft, means operated thereby for raising and lowering the elevator, valve means carried by the chamber member and opened by the receptacles when the same are raised by the elevator to permit liquid 15 to flow from the chambers to flow into the receptacles, each chamber having an opening in a side thereof and a tubular member of transparent material in communication with each opening and removably connected with the chamber carrying 20 member.

7. A receptacle filling device comprising a frame, a reservoir at the top of the frame, depending valve means carried by the reservoir, a vertically movable member having chambers 30 therein which when moved upwardly opens the valve means to permit liquid from the reservoir to pass into the chambers, valve means at the lower ends of the chambers, a conveyor for holding receptacles, an elevator for moving receptacles off the conveyor against the valve means of the chambers to open the valve means to permit liquid to pass from the chambers into the receptacles and then to lower the receptacles 35 back upon the conveyor, a pair of stop arms pivoted to the frame for holding receptacles on the conveyor under the valve means of the chamber member, means for normally holding said arms out of engagement with the receptacles, means on the elevator for moving the arms into the 40 path of the receptacles when the elevator is in lowered position, a second pair of arms pivoted to the frame and adapted to grip and hold a receptacle against movement by the conveyor when a proceeding group of receptacles are in filling 45 position, spring means for normally holding the last-mentioned arms in gripping position, means on the elevator for moving the last-mentioned arms into inoperative position, a drive shaft, cam means thereon for raising and lowering the 50 chamber member, a cam on the shaft and means operated thereby for raising and lowering the elevator, the last-mentioned cam acting to first raise the elevator and hold it in raised position until the receptacles are filled and this movement of the elevator releasing the clamping arms and also the first-mentioned arms and then said cam acts to lower the elevator a sufficient distance to place the receptacles on the conveyor and to engage the clamping arms to move them into 55 inoperative position and finally move the elevator to its fully lowered position to move the first-mentioned arms to holding position.

IRWIN I. KOTCHER.
